(57) **CLAIM**

The ornamental design for a battery housing for a solar light fixture, as shown and described.

DESCRIPTION

FIG. 1 is a rear side perspective view of the battery housing for a solar light fixture;

FIG. 2 is a front side perspective view of the battery housing for a solar light fixture;

FIG. 3 is a front elevation view of the battery housing for a solar light fixture;

FIG. 4 is another front elevation view of the battery housing for a solar light fixture with the solar panel removed for ease of illustration;

FIG. 5 is a rear elevation view of the battery housing for a solar light fixture;

FIG. 6 is a top plan view of the battery housing for a solar light fixture;

FIG. 7 is another top plan view of the battery housing for a solar light fixture with the solar panel removed for ease of illustration;

FIG. 8 is a bottom plan view of the battery housing for a solar light fixture;

FIG. 9 is a left side elevation view of the battery housing for a solar light fixture;

FIG. 10 is another left side elevation view of the battery housing for a solar light fixture with the solar panel removed for ease of illustration;

FIG. 11 is a right side elevation view of the battery housing for a solar light fixture; and,

FIG. 12 is another right side elevation view of the battery housing for a solar light fixture with the solar panel removed for ease of illustration.

The broken lines shown represent unclaimed subject matter and form no part of the claimed design. The unclaimed portion of the pole of the battery housing for a solar light fixture has been shown as broken in a middle portion to indicate indeterminate length.
